BOBBY PIN RECONDITIONING DEVICE

Thomas L. Adas, Chicago, Ill.

Application November 1, 1949, Serial No. 124,830

2 Claims. (Cl. 81—15)

1

My invention relates to a device for re-conditioning spread bobby pins and the like.

In applying a bobby pin to the hair, the two sides are spread apart from their normal mutually contacting relation to receive between them a tress of hair which the pin is to hold in place. Though bobby pins are made of tempered metal, in repeated use they soon become sprung so that they fail to reclose to properly hold locks of hair in place. To restore them to their original set by pinching between the fingers is impossible. Restoring the sprung pins by use of a pair of "pinchers" or pliers requires both an adeptness in manipulating the pin and tool and an understanding of the properties of metals which few bobby pin users possess, and is, in any case, difficult and tedious.

The principal object of my invention is to provide a very simple, inexpensive, small tool or implement by which even those least skilled in manipulating tools can easily, rapidly and surely restore spread bobby pins to proper condition for prolonged efficient re-use.

Other objects and advantages of the invention will be apparent from the following description with reference to the accompanying drawings in which

Figure 1 is a perspective view of one form of my bobby pin reconditioning implement in open condition with a badly sprung bobby pin inserted;

Figs. 2, 3 and 4 are plan, side elevational and end elevational views of the device of Fig. 1;

Figs. 5, 6 and 7 illustrate progressively the operation and effect of the device of Fig. 1 in re-storing a spread bobby pin; and

Figs. 8, 9 and 10 are plan, side and end views of a second form of my bobby pin restoring device.

The device of Figs. 1 to 7 comprises a small base member 11, having, on its upper side, two spaced studs or pins 12 and 13 and a pivot stud or pin 14 on which a cam lever 15 is swingably mounted. The lever 15 has a cam portion 16, shaped in accordance with the principles discussed hereinafter. In the example shown in Figs. 1 to 7, the periphery of the cam 16 is an arc centered at the point 17.

In this description and in the appended claims, references to the U-bent portion of the bobby pin are intended to designate the more or less semicircular bent yoke portion of the bobby pin and references to the ends of the U-bend or to the ends of the U-bent portion are intended to designate the points at which the ends of the

2

more or less semicircular yoke portion of the U join the more or less straight side legs of the U.

A sprung bobby pin B is laid flat on the upper side of the base 11 with its U-bent portion 5 between the studs 12 and 13 and the cam 16. The pin is placed into contact with both of the studs 12 and 13, the stud 12 engaging the pin at about the middle and the stud 13 contacting at about one end of the U-bent portion. The lever 15 is swung toward the bobby pin to bring its cam edge 16 into engagement with the pin near the other end of the U-bent portion as shown in Fig. 5. By continuing closing movement of the lever 15, the cam 16, sliding a little 10 on the bobby pin as it urges the pin against the stud 12, presses the ends of the U-bent portion of the pin together as shown progressively in Figs. 6 and 7. In Fig. 6, the two sides of the bobby pin are in their normal positions relative to each other. If the movement of the lever 15 were reversed at this point, the bobby pin would spring back part way and the sides would again separate a little. However, the closing movement 15 of the lever 15 is continued until the two sides 20 of the bobby pin, rocking relatively to each other about their point of mutual contact C nearest to the U-bent portion, separate a little at their free ends. Thereafter, upon relieving finger pressure 25 on the lever 15 and permitting it to move reversely, the U-bent portion of the bobby pin springs back sufficiently to bring the free ends of its sides again into pressure contact without separating at their innermost point of contact, i. e., the sides of the pin are again in pressure contact with each other throughout or at spaced 30 points as when new.

Forms of bobby pins vary somewhat, some having their sides substantially straight and initially 35 in contact with each other throughout the major part of their lengths, and some having one side of an undulating form, as shown in Fig. 6, so that it can contact the other side at a number of spaced points. Some also have both sides, 40 whether smooth or undulating, curved arcuately in the same direction on a rather large radius. The dimensions of the U-bent part may also vary. The implement of my invention has the advantages of being capable of properly reconditioning 45 bobby pins of all sizes and shapes presently used, and of being so simple, easy and rapid in use that any bobby pin user may properly recondition a large number of bobby pins by means of my device in a very short time. Further, the 50 new device is small and light and well adapted 55

to be carried in a small purse along with the numerous other articles usually found therein.

It has been found that the relative positions of the studs 12 and 13 and of the pivot 14 should be rather close to those shown in Figs. 1 to 7 where the center of pivot 14 is on one side 18 of a right angle, the two sides 18, 19 of which are outwardly tangent to the pins 12 and 13, respectively, at equal distances from the vertex of the angle. In other words, the centers of the studs are on a line which forms an angle of substantially 135° with that extended line from the center of the pivot 14 which is tangent to the stud 12 on the side nearest the stud 13. As already mentioned, the edge of the cam 16 is an arc centered at 17. It will be further noted that the ratio of the distance from the cam center 17 to the center of the pivot 14 is more than half the radius of the cam. These relationships may be varied a little, provided that, during the closing movement of the cam lever 15, the cam 16, acting frictionally on the side of the bobby pin near one end of the U-bent part, urges the bobby pin against the studs 12 and 13, and further provided that, during that portion of the reconditioning operation from the stage of Fig. 6 to the final stage of Fig. 7, the pin 13 and the cam 16 press on the bobby pin at substantially the ends of the U-bend of the latter rather than on the sides of the pin at any substantial distance from the ends of the U-bend.

As a specific example, a device of the form shown in Figs. 1 to 7 with the following dimensions has been found to operate excellently on a very wide variety of currently used bobby pins: The studs are one-eighth inch in diameter spaced one-fourth inch between centers. The center of the pivot is twenty-one sixteenths of an inch from the center of the stud 12. The cam has a radius of curvature of one-half inch with its center five sixteenths of an inch from the center of the pivot 14. The ratio of the distance from the pivot center to the center of the cam arc to the radius of the cam arc may vary somewhat but it is considered preferable to keep this ratio between one-half and three-fourths. The overall length may vary considerably but about three inches will be found convenient.

The device may be made of various materials. For example, the entire device may be of metal, the parts 11 and 15, 16 being stamped or otherwise cut from one-eighth inch sheet. The parts 11 and 15, 16 or either of them might be made of a relatively hard and tough sheet of plastic with the studs 12, 13 and 14 of metal set into the part 11. Also, two principal parts might be cast or molded with integral studs.

Figs. 8, 9 and 10 show a form of my device which may be molded of a hard, tough, thermosetting plastic such as a polystyrene resin. This form of my device is formed entirely of molded plastic except that the pivot for the cam lever 20 is a hollow rivet or eyelet 21. In place of the two studs 12 and 13 of the device of Figs. 1 to 7, the device of Figs. 8, 9 and 10 has rounded angular boss 22 formed integrally with the base 23 and adapted to engage the U-bent part of a bobby pin at or close to the same points at which the latter would be engaged by the studs 12 and 13 of the device of Figs. 1 to 7. In other respects, the form of the device of Figs. 8, 9 and 10 may be like that of the device of Figs. 1 to 7.

The form of my device shown in Figs. 8, 9 and 10 may, alternatively, be made of metal, such as cold drawn aluminum, formed in coining dies.

I claim:

- 20 1. A device for reconditioning bobby pins and the like comprising, a base plate having a substantially flat continuous surface, a lever pivoted adjacent an end thereof to said base plate on an axis normal to said surface and for swinging movement closely adjacent said surface, an edge of said lever adjacent said axis being formed as an arcuate cam surface of substantial width extending substantially to said continuous surface of said base and generally normal thereto, a pair of spaced abutments fixed to said base plate and extending substantially normal to said continuous surface, said abutments being spaced from said pivot axis and arranged to define, with said arcuate cam, a pocket adapted to receive the U-bend of a sprung bobby pin with its leg portions lying flat against said continuous surface, said abutments having work-engaging portions lying respectively in the two sides of a right angle, one of the sides of which passes through the pivot axis, said portions being substantially equidistant from the vertex of said right angle.
- 25 2. A device according to claim 1, wherein said abutments are provided by an angular boss formed integrally with the base plate.
